(57) **CLAIM**

I claim the ornamental design for a weight shroud, as shown and described.

DESCRIPTION

FIG. 1 is a front perspective view of my weight shroud shown in association with an exercise machine which is shown in dotted lines for illustrative purposes only and to which no claim is made;

FIG. 2 is a front view elevational view thereof with the dotted lines showing being for illustrative purposes only and to which no claim is made;

FIG. 3 is a right side elevational view thereof;

FIG. 4 is a back view thereof;

FIG. 5 is a left side elevational view thereof;

FIG. 6 is a top view thereof;

FIG. 7 is a bottom view thereof;

FIG. 8 is affront view of an alternative embodiment of my wieght shroud showing my device in broken line to designate indeterminate width and height, with the broken lines showing being for illustrative purposes only;

FIG. 9 is a right side elevational view of the alternative embodiment shown in FIG. 8;

FIG. 10 is a rear view of the alternative embodiment shown in FIG. 8;

FIG. 11 is a left side elevational view of the alternate embodiment shown in FIG. 8;

FIG. 12 is a top view of the alternative embodiment shown in FIG. 8; and,

FIG. 13 is a bottom view of the alternative embodiment shown in FIG. 8.

The portions shown in broken lines are for illustrative purposes only and form no part of the claimed design and to which no claim is made.
